CLAIM

The ornamental design for a cap strap cover, as shown and described.

DESCRIPTION

FIG. 1 is a front perspective view of a cap strap cover showing my new design, the broken line showing of the cap, the rear strap, and the word logo is for illustrative purposes only and forms no part of the claimed design;
FIG. 2 is an exploded front perspective view thereof, with a portion of the cap strap shown in broken lines;
FIG. 3 is a front elevational view thereof;
FIG. 4 is a rear elevational view thereof;
FIG. 5 is a top plan view thereof;
FIG. 6 is a bottom plan view thereof;
FIG. 7 is a left end view in elevation thereof, the end opposite being a substantial mirror image thereof; and,
FIG. 8 is a profile view taken along line 8—8 of FIG. 3.
